UNITED STATES PATENT OFFICE.

ALBERT O. WHITNEY, OF BRONXVILLE, AND CHARLES L. WEYAND, OF NEW YORK, N. Y.

FACING FOR WALLS AND OTHER SURFACES.

No. 851,579.

Specification of Letters Patent.

Patented April 23, 1907.

Application filed November 19, 1906. Serial No. 343,960.

To all whom it may concern:

Be it known that we, ALBERT O. WHITNEY and CHARLES L. WEYAND, both citizens of the United States, ALBERT O. WHITNEY residing at Bronxville, county of Westchester, and State of New York, and CHARLES L. WEYAND residing at the city of New York, county and State of New York, have invented jointly a certain new and useful Facing for Walls and other Surfaces, of which the following is a specification.

This invention is a facing for walls and other surfaces, and the object in view is to provide a substitute for ceramic tiling now used largely in lavatories, bath rooms, and numerous other places.

The wall facing of this invention may be regarded as metal tiling from the fact that it is composed of a sheet of material, usually metal, the exposed surface of which is treated to make it resemble a wall or facing composed of glazed tiles. The treatment referred to consists of embossing the sheet material to produce thereon the imitation longitudinal and cross lines at the joints or bonds between ceramic tiles, and a coating of enamel which not only makes the material resemble ordinary glazed tiling, but performs the important function of a preservative coating for the sheet material in preventing corrosion thereof, and the still further and important function of making the material thoroughly hygienic and sanitary.

The enameled and embossed sheet material of our invention is constructed with the especial purpose of installing it in a manner to produce practically invisible joints between the edges of adjacent sheets, such invisible joints being at the end edges, or the side edges, or both, of a plurality of sheets employed as a facing for walls, ceilings, and numerous other surfaces.

In the accompanying drawings we have shown one embodiment of the invention, but the construction shown therein is to be understood as illustrative only, and not as defining the limits of the invention.

Figure 1 is a side elevation representing a portion of two sheets constructed in accordance with our invention, and joined along their longitudinal meeting edges by a substantially invisible joint; Fig. 2 is a vertical cross-section, on an enlarged scale, on the line 2-2 of Fig. 1; Fig. 3 is a side elevation

of two sheets having interlocking relation, 55 and joined along the adjacent edges thereof by a substantially invisible joint, as contemplated by this invention; and Fig. 4 is a horizontal section on the irregular line 4-4 of Fig. 3. 60

Referring more particularly to Figs. 1 and 2 of the drawings, A, B, designate two sheets of material constructed in accordance with our invention, for the purpose of providing a metallic tile facing for walls, ceilings and 65 other surfaces. Each sheet of material consists, preferably, of a metallic base *a*, and a coating of enamel *b*, the latter being applied to the metallic base in any suitable or preferred way. The coating or layer *b* of enamel 70 is preferably baked on the metallic base sheet *a*, and said coating protects the metallic sheet from oxidation or corrosion under atmospheric changes, as well as preventing deterioration of the metallic base sheet, 75 thereby producing an ornamental and sanitary article of commerce.

As shown, the sheets A, B, are embossed for the purpose of making them resemble ceramic tiling, and the enameled coating *v* of 80 said sheets gives them the effect of glazed tiling. While the embossing of the sheets A, B, may be of any suitable nature, still in the embodiment of the invention shown by Figs. 1 and 2, such embossing produces parallel rows of channels *c*, which extend longitudinally of the sheets, and transverse channels *d*, each opening into the longitudinal channels *c*, thereby dividing the surface of the sheet into parallelograms which are defined or bounded by the channels *c*, *d*, the latter representing the mortar joints, or bonding material between the rows of ceramic tiling. 85 90

In the installation of high grade enameled facings for walls, ceilings and the like, it is 95 essential to join the adjacent sheets in a way which will practically conceal or make invisible the line of juncture between two or more joints. We accomplish this object by providing a semi-channel at one or more 100 edges of each sheet, and these sheets are assembled into abutting relation so that the semi-channels of the two sheets will meet each other, and thereby produce a complete channel, the line of juncture being along the 105 bottom of the channel.

In the construction of Figs. 1 and 2, the sheet A is provided, at its lower edge, with a

semi-channel *e*; whereas the sheet B is provided at its upper edge with a semi-channel *f*. In the installation of the two sheets, A, B, the semi-channeled edges *e*, *f*, are assembled into abutting relation along the aforesaid edges, thereby producing a joint D, which is at the bottom of the channel produced by the registration of said semi-channeled edges *e*, *f*, see Fig. 2. Although we have shown and described the sheets A, B, as the upper and lower sheets which are united at the lower and upper edges, respectively, of said sheets, it will be understood that each edge of each sheet may be joined to other sheets in a similar way, or by similar joints, as for example, the top edge of the sheet A may be joined by a substantially invisible joint with the bottom edge of another sheet next above it, or either or both end edges of the sheets, A or B, may be joined to other sheets placed to the right or left thereof in substantially the manner herein indicated.

In the manufacture of each sheet of material, A or B, we may employ any suitable metal of the required thickness, length, and width, and in some instances, we have employed copper, zinc, and various other metals, or alloys of metals. The metal base sheet having been properly cleansed, we apply a coating of enamel to one surface of the sheet, and said enameled coating is smoothed and baked, thus producing the glazed effect which it is desired to impart to the sheet. We emboss the sheet either before or after baking the enamel thereon, and this embossing may be of any suitable pattern, ornamental or otherwise. As shown, the embossing produces the longitudinal and transverse channels which give the sheet the appearance of ceramic tiling, and after the embossing operation is completed, the sheet is cut or trimmed to the desired dimensions, care being taken to trim the edge or edges along the bottom portion of one of the channels thereof for the purpose of producing the partial or semi-channel *e* or *f*, as hereinbefore described. The sheets thus prepared are ready for the market, and may be installed quickly, by unskilled labor, and economically.

In Figs. 3 and 4 of the drawings, we have represented another embodiment of the invention wherein sheets A', B', are assembled in interlocking relation along their meeting vertical edges. It should be understood that each sheet A', B', consists of a metallic base sheet *a'*, and a coating *b'* of enamel, each of said sheets being, also, provided with longitudinal and transverse grooves *c'*, *d'*, which are produced by embossing the previously enameled layers of material *a'*, *b'*, substantially as hereinbefore described. The sheet A' is provided along one of its vertical edges with notches *E*, *E'*, *E''*, thereby producing tongues *F*, *F'*. A semi-channel *g*

extends around the edge portions of the notches and the tongues of said sheet A'. The other sheet B' is provided with tongues *H*, which are separated by notches *I*, and around said tongues *H*, and notches *I*, extends a continuous groove or semi-channel *h*. The notches and tongues of the sheet A' correspond to the notches and tongues of the sheet B', and each semi-channel, *g* or *h*, constitutes one half of a channel or groove. The sheets A', B', are assembled for the tongues of one sheet to fit into the notches of the other sheet, and vice versa, and the said channeled edges *g*, *h*, abut and register so as to produce an irregular joint D', the latter being formed by the semi-channel *g*, of the sheet A', and the semi-channel *h* of the sheet B'. It will be understood that the two sheets are assembled into abutting and interlocking relation for the purpose of arranging them in the same plane, so that the joint D' will be practically invisible. The installation and assemblage of the sheets may be carried out very easily and quickly, and the surface of the wall, ceiling, or the like, is ornamented and protected by a facing which, in all respects, resembles ceramic tiling, and possesses good wearing and cleaning properties.

One of the important advantages of this invention resides in a construction of wall or ceiling facing which can be bent to conform to the surface to which it is applied without injury to the enameled coating.

It will be understood that the facing shown by Figs. 3 and 4, may be supplemented by the addition of other sheets of material, such as the sheets A, B, of Figs. 1 and 2.

Having thus described our invention, what we claim as new, and desire to secure by Letters Patent, is:—

1. A facing for walls, ceilings, and the like, comprising enameled material in sheet form, each sheet being provided with notches and tongues, and said sheets being assembled in edgewise abutting relation, with the tongues of each sheet filling the notches of the next sheet.

2. A facing for walls, ceilings, and the like, comprising enameled and channeled material in sheet form, one or more edges of the sheet being, substantially, at the bottom of the channel next to said edge, whereby adjacent sheets may be assembled in edgewise abutting relation.

3. A facing for walls, ceilings, and the like, comprising enameled and channeled material in sheet form, an edge portion of the sheet being cut through the bottom portion of one of the channels therein, whereby adjacent sheets are adapted to be assembled for the semi-channeled edges of said sheets to abut one another.

4. A facing for walls, ceilings, and the like, comprising channeled material in sheet

form, an edge portion of the sheet being cut or trimmed along the bottom portion of a channel therein, the cut or line of severance being substantially along the central line of the channel.

5. A facing for walls, ceilings, and the like, comprising a plurality of enameled and channeled sheets assembled in abutting relation, the sheets joining one another along semi-channeled edges thereof.

6. A facing for walls, ceilings, and the like, comprising a plurality of enameled and channeled sheets each having notches and tongues, said sheets being assembled in interlocking order and in edgewise abutting relation.

7. A facing for walls, ceilings, and the like, comprising a plurality of enameled and channeled sheets each having notches and tongues, said sheets being assembled in interlocking order and in edgewise abutting relation, and the sheets joining one another along semi-channeled edges thereof.

8. A facing for walls, ceilings, and the like, comprising a plurality of channeled sheets having at their meeting edges interlocking

tongues and grooves, said sheets meeting along semi-channeled edges thereof.

9. A facing for walls, ceilings, and the like, comprising a channeled sheet, the edge of which is provided with a semi-channel, whereby a plurality of sheets may be assembled in edgewise abutting relation at the semi-channeled portions thereof.

10. A facing for walls, ceilings, and the like, comprising a channeled sheet, having a tongue and a notch at one or more of the edges thereof, said sheet having a semi-channel at one or more of its edges, whereby a plurality of sheets are adapted to be assembled in interlocking and edgewise abutting relation along the semi-channeled edges thereof.

In testimony whereof we have signed our names to this specification, in the presence of two subscribing witnesses.

ALBERT O. WHITNEY.

CHARLES L. WEYAND.
